UNITED STATES PATENT OFFICE.

JOSÉ ARBAT, OF NEW YORK, N. Y.

TARGET.

No. 884,972.

Specification of Letters Patent. Patented April 14, 1908.

Application filed October 29, 1907. Serial No. 399,632.

To all whom it may concern:

Be it known that I, JOSÉ ARBAT, a subject of the King of Spain, and a resident of the city of New York, borough of Manhattan, in the county and State of New York, have invented a new and Improved Target, of which the following is a full, clear, and exact description.

This invention relates to targets, and it is particularly useful in connection with shooting galleries, rifle ranges and the like.

An object of the invention is to provide a simple and inexpensive target for use in shooting galleries, rifle ranges and the like, which has a target disk or object provided with a movable bull's-eye controlling a movable figure, which when the bull's-eye is struck by a bullet, advances toward the shooter and tenders the latter a prize or executes some other evolution or movement indicative of the shooter's success in striking the object.

A further object of the invention is to provide a device of the class described, having a house normally concealing a figure arranged to travel upon a track toward the position of the shooter, and an object having a movable bull's-eye, controlling the door of the house and provided with means for returning the figure to the house.

The invention consists in the construction and combination of parts to be more fully described hereinafter and particularly set forth in the claims.

Reference is to be had to the accompanying drawings forming a part of this specification, in which similar characters of reference indicate corresponding parts in all the views, and in which

Figure 1 is a side elevation of my invention showing parts in cross-section and parts in different positions in dotted outline; Fig. 2 is an enlarged horizontal section of the house, showing certain parts in different positions in dotted outline, and illustrating a portion of the track upon which the figure travels; Fig. 3 is an enlarged vertical section on the line 3—3 of Fig. 1; Fig. 4 is an enlarged vertical section showing the object and a part of the house, together with the releasing mechanism for the door of the house; Fig. 5 is a transverse section on the line 5—5 of Fig. 6; Fig. 6 is a plan view showing a portion of the track near the position of the shooter; and Fig. 7 is a vertical section of the

figure, showing certain parts in different positions in dotted outline.

Before proceeding to a more detailed explanation of my invention, it should be understood that the figure is normally maintained in a concealed position within the house, and does not advance from the latter until the bull's-eye of the target is struck by a bullet. When this occurs, the bull's-eye, which is movable, actuates a suitable releasing mechanism, and the doors of the house which are provided with springs for the purpose, are allowed to open. The figure then advances from the house and travels gravitationally along a suitable track to a point near the position of the shooter. The figure may be of any suitable form consisting, for example, of a model or representation of a human being, and is arranged to carry a prize or other mark indicative of the shooter's success in striking the bull's-eye. The arrangement is such that as the figure approaches the shooter, a trip upon the track actuates a suitable mechanism which causes the figure to execute a movement, for instance, a nod or bow of the head in case the figure is a representation of a person. The end of the track adjacent to the position of the shooter is elevated, to bring the figure substantially to a stop without jar or danger of upsetting the same. This end of the track is so arranged that it can be elevated a suitable distance to permit the figure to return gravitationally to the house. The movement of the figure into position within the house, closes the door or doors of the same so that the target is set for further use.

Referring more particularly to the drawings, 1 represents a shooting gallery or rifle range of the usual type. A stand 2 is provided for the persons practicing upon the targets of the range, and has a shelf or rail 3 limiting the distance to which they can approach with respect to the target. The objects at which the shooters fire may be of any shape or form suitable for the purpose, each consisting, for instance, of the usual disk 4. It should be understood that any form of object can be employed, so long as the latter has a bull's-eye or particular portion corresponding to a bull's-eye, and which it is desired to strike. In the form of object illustrated in the accompanying drawings, the object disk 4 is mounted upon a suitable wall 5 arranged near the front edge of the

top 6 of a house 7 and braced thereupon by means of suitable rod 8. The house 7 is preferably mounted on uprights or standards 9, to elevate the house above the ground.

5 The parts may be fashioned from any suitable material such as sheet iron, wood or the like. The object disk 4 has an opening 10 therethrough, in which is arranged a movable member 11 constituting the bull's-eye of the target. The member 11 has a shank 12 extending through a constricted opening 13 of the wall 5. The constricted opening is smaller than the member 11 and thus limits the movement of the latter. A cross pin 14 limits the movement of the member 11 in the opposite direction. A bracket 15 is rigidly arranged upon the top 6, and carries a movable arm 16 consisting preferably of a bent or curved rod as is shown most clearly in Fig. 4. At the upper end the arm 16, which is movably arranged in a notch 17 of the bracket, has a head 18 against which the shank 12 of the movable member 11 can strike. The opposite end 19, of the arm 16 is bifurcated and is pivotally secured to a catch rod 20, slidably arranged in a hollow guide 21, and extending through an opening in the top 6. At the end within the house, the catch rod has a catch tongue 22. The guide 21 is held in place by means of a suitable bracket 23, and at the upper end has a hollow head 24, provided with edge recesses 25. A pin 26 carried by the catch rod, seats within the recesses 25 and limits the downward movement of the catch rod.

At the side edges of the front of the house 6, are mounted swinging doors 27, by means of suitable hinges 28 provided with springs 29, which tend to force the doors to open. A catch 30 is mounted at the inner side of the edge of the doors, and is adapted to operate with the catch tongue to hold the doors in a closed position. A helical spring 31, arranged upon the catch rod, normally projects the catch tongue downward in position within the catch 30, as is shown most clearly in Fig. 4. When the movable member 11 is struck by a bullet it is forced inward and the shank 12 engages the head 18 of the arm 16, operating the arm to raise the catch rod 20. The upward movement of the latter releases the tongue from the catch 30, and permits the door to swing open under the influence of the springs 29.

55 A support 32, is arranged centrally between the target and the position of the shooter, and has a top 33 upon which is movably arranged a track 34; the latter consists preferably of rails 35 of the usual form, joined by cross ties 36. One end of the track extends into the house 7 while the other end extends to the rail or shelf 3. The track is arranged to pivot upon the support to a certain extent, so that when one end is correspond-

ingly depressed. A spring 37 within the house 7, holds the track in a normal position with the end remote from the house slightly lower than that within the house.

The figure 38, which may be of any preferred or common form and consist of a representation of a human being, an animal or the like, is mounted upon a car 39 having wheels 40 arranged to travel upon the track rails. The figure is normally held in position within the house by the doors of the latter; when these are released the figure moves out along the track under the influence of gravity, and near the center, that is, adjacent to the support 32, the track has a downward dip or concavity. Thus as the figure advances from the house its speed toward the support 32 gradually increases, while its movement from the support to the position of the shooter is correspondingly retarded and the figure is thus gently brought to a stop near the shooter. When it is desired to return the figure to the house, the end of the track adjacent to the shooter's position is elevated by means of a suitable elevating rod 41. The latter is slidably mounted in brackets 42, arranged upon one of the rail or shelf supports, and at the upper end engages a cross tie 36 of the bracket. At the opposite end the elevating rod has a head 43 adapted to be engaged by a lever 44, carried by a suitable pivoting bracket 45, mounted upon the rail support. The lever 44 can be manually or pedally controlled to elevate the adjacent end of the track. When this is effected, the figure rolls back along the track to a position within the house. The figure enters the house, and a stud 46 on the carriage 39 engages a stop 47 pivotally connected at the adjacent ends of similar links 48, the opposite ends of which are respectively secured to the opposite doors of the house. The stop 47 is arranged to travel within a guideway 49 arranged upon the bottom of the house. As the carriage enters the house the stud carries with it the stop 47 and thereby the doors, through the links 48, are closed by the movement of the carriage itself. At the same time, the stop 47 serves to arrest the movement of the carriage. It will be understood that the doors 27 have suitable openings or recesses 50, 51 to receive the track rails 35, the links 48 and the guideway 49.

In the form of the device illustrated in the accompanying drawings, the figure 38 employed consists of the representation of a woman having the arms outstretched, and carrying a tray 52, upon which may be placed the prize awarded to the shooter for striking the bull's-eye. The head 53 of the figure is pivoted in a suitable opening at the upper portion of the same and has an arm 54 to which is secured a spring 55, the other end of which is fixed to the figure. A second arm 56 is pivotally connected with a link 57, 130

the opposite end of which is connected to a pivoted bell crank lever 58. An arm 58^a of the latter extends through a suitable opening 59 in the carriage toward the track rails. The projecting arm 58^a of the bell crank lever 58 is hinged as is shown most clearly in Fig. 7. Near the shooter's position the track has a projection 60 adapted to engage the arm 58^a of the bell crank lever. When the bell crank lever is actuated by such engagement of the arm 58^a the head of the figure is caused to bow or nod by means of the link 57 and the spring 55, thereby executing a movement indicative of appreciation of the success of the marksman. Owing to the hinge construction of the arm 58^a, the lever is operatively engaged by the projection 60, only when the figure is traveling in one direction along the track. Thus, the figure can return to the house without a movement of the head or other parts actuated by the projection 60. It will be understood that figures of different kinds can be employed and can be caused to execute different movements, and movements of different parts of the bodies effected by similar mechanism.

Having thus described my invention, I claim as new and desire to secure by Letters Patent:

1. A target, comprising an object arranged to move under impact, a house, a figure adapted to be normally arranged within said house and on being released to advance to a point remote from said house, means for concealing said figure within said house, and means operable by a movement of said object for releasing said first means.

2. A target, comprising an object arranged to move under impact, a house, a figure adapted to be normally arranged within said house and on being released to advance to a point remote from said house, means for concealing said figure within said house, means permitting the movement of said figure from said house, means operable by a movement of said object for releasing said first means, and means for returning said figure to said house.

3. A target, comprising an object having a movable portion, a house having a closure, means operable by said movable portion of said object for releasing said closure, a track, and a figure arranged to travel upon said track and normally concealed within said house.

4. A target, comprising an object having a movable portion, a house having a closure, means for normally locking said closure, means operable by said movable portion for releasing said closure, a track, and a figure arranged to travel upon said track and normally concealed within said house and held in position therewithin by said closure.

5. A target, comprising an object having a movable bull's-eye, a house having a resili-

ently controlled door, means for holding said door closed, means operable by said bull's-eye for releasing said door, a track, and a figure arranged to travel upon said track and normally concealed within said house. 70

6. A target, comprising an object having a movable bull's-eye, a house having a resiliently controlled door, means for holding said door closed, means operable by said bull's-eye for releasing said door, a track, a figure arranged to travel upon said track and normally held within said house, said figure being held within said house by said door when the latter is closed, and means operable by a movement of said figure for closing said door. 80

7. A target, comprising an object having a movable bull's-eye, a house having a door, resilient means for opening said door, means for holding said door closed, means operable by said bull's-eye for releasing said door, a pivoted track having an end arranged within said house, a figure adapted to travel upon said track and normally concealed within said house, and means for operating said track to cause said figure to travel gravitationally upon the same. 90

8. A target, comprising an object having a movable bull's-eye, a house having a door, resilient means for opening said door, means for holding said door closed, resiliently controlled means operable by said bull's-eye for releasing said door, a pivoted track having an end within said house, a figure arranged to travel upon said track, means for holding said track in a normal position, means for operating said track to cause said figure to travel gravitationally along the same, and means operable by a movement of said figure, for closing said door. 95

9. A target, comprising an object having a movable bull's-eye, a house having a door, resilient means for opening said door, a figure adapted to be concealed within said house by said door, means for holding said door closed, and a movable member controlling said means and operable by said bull's-eye. 105

10. A target, comprising an object having a movable bull's-eye, a house having a door, resilient means for opening said door, a figure adapted to be concealed within said house and to be held in a concealed position by said door, a catch carried by said door, a resiliently controlled latch adapted to engage said catch to hold said door closed, and a movable member pivoted at one end to said latch and having the other end arranged adjacent to said bull's-eye, said member being operable by a movement of said bull's-eye to disengage said latch and said catch. 115

11. A target, comprising an object having a movable portion, a house having a door, a figure movable into and out of said house and adapted to be normally concealed therewithin, said door being adapted to hold said 130

figure within said house and to conceal the same, resilient means for opening said door, means for locking said door in a closed position, means operable by a movement of said 5 movable portion for releasing said door, and means controllable by a movement of said figure for closing said door.

12. A target, comprising an object having a movable bull's-eye, a house having a door, 10 resilient means for opening said door, means controlled by said bull's-eye for locking said door in a closed position, a figure movable into said house and out of the same, said figure being adapted to be concealed within said 15 house and held in position therewithin by said door, a link for operating said door, and means for guiding an end of said link, said figure having means for engaging said link to close said door.

16. A target, comprising an object having a movable bull's-eye, a house having doors, 20 resilient means for opening said doors, means for locking said doors in a closed position, means controlled by said bull's-eye for releasing said doors, each of said doors having a link controlling the same, the adjacent ends of said links being pivotally connected, a stop secured to said links at the adjacent ends, and means for guiding said stop, said 25 figure having a projection adapted to engage said stop to operate said links to close said doors.

14. In a target, an object having a movable portion, a track, a figure movable longitudinally of said track, means for controlling said figure, means operable by said movable portion for disclosing and releasing said figure, means for operating said track to cause said figure to travel gravitationally along 30 the same, and resilient means for holding said track in a normal position.

15. A target, comprising an object having a movable portion, a track movably supported at a point intermediate of the ends 35 thereof, a figure arranged to travel along said track, a house for concealing said figure and holding the same concealed, and means operable by said movable portion for releasing said figure from said house, said track having an end extending into said house, 40 said track having resilient means for holding said track in a normal position, and means for elevating said track at one end of the same to cause

said figure to travel gravitationally upon said track.

16. A target, comprising an object having a movable portion, a track having a depressed section near the middle, means for pivotally supporting said track, a figure arranged to travel upon said track, a house for concealing said figure, means operable by said movable portion for releasing said figure from said house, means for resiliently holding said track in a normal position, and a lever serving to raise said track near an end 65 of the same to cause said figure to travel gravitationally thereupon.

17. A target, a figure adapted to be controlled by an object under impact, means for concealing said figure, means for releasing it from concealment, said figure comprising a carriage adapted to travel upon a track and having a movable portion, said figure further having means operable by said track for causing said movable portion to be actuated.

18. In a target, a figure controlled by an object adapted to move under impact, means for concealing said figure, means for releasing said figure from concealment, said figure comprising a wheeled carriage, a body having a movable portion, a link for operating said movable portion, resilient means for resisting the movement of said movable portion, and a lever operable by engagement with said track to actuate said movable portion.

19. A target, comprising an object arranged to move under impact, a figure arranged to travel to a point remote from said object and normally concealed, and means operable by a movement of said object for causing said figure to appear and to travel.

20. A target, comprising an object arranged to move under impact, a figure arranged to travel to a point remote from said object, means for concealing said figure, and means operable by a movement of said object for releasing said figure to appear and causing said figure to appear and to travel.

In testimony whereof I have signed my name to this specification in the presence of two subscribing witnesses.

JOSÉ ARBAT.
